G. COENEN.
FLUSHING APPARATUS.
APPLICATION FILED JAN. 9, 1908.

935,642.

Patented Oct. 5, 1909.

UNITED STATES PATENT OFFICE.

GERHARD COENEN, OF HOBOKEN, NEW JERSEY

FLUSHING APPARATUS.

985,642.

Specification of Letters Patent. Patented Oct. 5, 1909.

Application filed January 9, 1908. Serial No. 409,988.

To all whom it may concern:

Be it known that I, GERHARD COENEN, a subject of the Emperor of Germany, residing in Hoboken, county of Hudson, New Jersey, have invented a certain new and useful Improvement in Flushing Apparatus; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

My invention relates to water-closet systems and it has for its object to provide an improved simple, reliable and generally substantial flushing apparatus for such systems whereby the closet is normally free of water and only contains water at the periods of its use, so that it is proof against freezing and may therefore be disposed in out-of-door or other more or less exposed places.

I have fully illustrated my invention in the accompanying drawing, wherein the apparatus is shown in general in section, certain parts appearing, however, in side elevation.

In said drawing, *a* designates the bowl of the closet, the same having the usual siphon discharge *b*, and *c* is its flush pipe leading downwardly thereto from the tank *d*; by means of the hinge *e* the seat and its cover, marked *f* and *g*, are arranged on the bowl *a*, the part of the hinge member *e* which carries the seat and which is marked *i* having a downward projection *j* formed at the back of the seat and the part of said hinge which is marked *k* and carries the cover having an upward projection *l*. The purpose of these projections will appear later.

The tank-supply pipe *m* is controlled by the means shown at the base of the bowl in such manner that water is admitted to the tank only when the seat is pressed down, *i. e.*, occupied, or thrown full back. This means comprises the valve-casing *n* having two compartments *o* into which, respectively, lead the portions of the supply pipe *m*, said compartments being separated by a substantially horizontal wall *p* having a port *q*; the top of the valve-casing is formed as a nipple *r* into which is screwed the lower end of the tubular guide *s* for a spindle *t* carrying a valve *u* adapted to seat on wall *p* over port *q*, said valve being normally held

against its seat by a spring *v* coiled about the spindle and interposed between the valve *u* and the top of the nipple. A chamber *w* is formed in the bottom of the valve-casing *n*, the same having a drain port to the sewer marked *x*, and also having an opening *y* at the top which affords a guide for the lower end of the spindle *t*. In the portion of the spindle which immediately stands in the opening *y* when the spindle is in its normal position as hereinbefore stated, said spindle is reduced, as at *z*, while below its grooved portion it is externally cylindrical so that it substantially snugly fits the opening *y*; in the normal position of the spindle, therefore, water may pass from the lower compartment of the valve casing through the chamber *w* and pass out at the port *x*, while, when the spindle is raised so as to unseat valve *u*, its cylindrical portion closes the opening *x*, preventing the admission of water into said chamber.

The guide *s* is formed with a bracket *1* in which is fulcrumed a lever *2* which is attached to the upper end of the spindle. To this lever is connected a link *3* which is in turn connected with a lever *4* fulcrumed in the fixed part of the hinge *e* and formed with two cam surfaces *5* and *6* respectively *85* adapted to be engaged by the projections *j* and *l* of the seat and cover. When the seat is pressed down, its projection *j* engages the cam-surface *5* and effects the raising of the spindle and consequently of the valve *u*; the same effect occurs when the seat and cover are raised sufficiently to bring the projection *l* against the cam-surface *6*.

The tank *d* is formed with a hole *7* through which projects the neck *8* of an upright tubular casing *9* arranged in the tank and secured therein by a nut *10* screwed on its neck and clamping it to the bottom of the tank; said nut forms a union between the pipe *m* and the casing *9*. In the casing *9* is arranged to move vertically a float *11* having a stem *12* which projects through the top of the casing and is connected with the usual tubular valve *13*, which controls the discharge from the tank by way of the pipe *c*, by means of the lever *14*, fulcrumed at *15*. The float approximately, though not perfectly, fits the casing *9* so that while the casing affords a guide therefor in its vertical movements water can pass the float in order to find its way out of the casing by the discharge nozzle *16* which is attached to the

casing near the top thereof. The nozzle is formed with a bracket 17 serving as a fulcrum for the stem of the lever 18 which carries the ball-float 19 and is adapted to control the discharge of water from the nozzle, shutting off the flow when the water raises the float to a certain elevation and permitting its escape when the tank is empty and the float is down, all according to a construction and operation well-known in the art.

The operation of the apparatus is as follows: Normally the tank is empty, as is also the pipe *m* which has an outlet to the sewer by way of the port *x* because at this time, the seat being unoccupied and not raised to its full-back position, the spring *v* holds the spindle *t* down so that the reduced or recessed portion *z* of the spindle registers with the opening *y* of the chamber *w*. Upon the seat being occupied, or being raised sufficiently, so that the spindle is elevated and the valve *u* lifted from its seat, the water flows through the valve-casing *n* and pipe *c* into the tubular casing *g*, raising float 11 and finding its way out of the casing *g* by the discharge nozzle 16 which at this time is open because, the tank being empty, the ball-float is depressed. When the float 11 rises, it moves lever 14 and so depresses the tubular valve 13, said valve closing the escape from the tank by way of the flush-pipe *c*, so that the water begins to fill the tank; when the tank is full, the ball-float rises and, by means of its stem 18, cuts off the discharge

of water into the tank. Upon the seat being now released and allowed to assume its normal position, the spring *v* re-seats valve *u*, cutting off the supply of water to the tank. At the same time, the spindle *t* opens the way to the sewer through the opening *y* for so much of the water as remains in the pipe *m* and the casing *g*, allowing the float 11 to fall and so effect the raising of the valve 13; this starts the flushing operation and results in emptying the tank and the pipe *c* of all water contained therein. The apparatus now stands in its normal condition, free of all water.

Having thus fully described my invention, what I claim and desire to secure by Letters Patent is:

In a water-closet, the combination of a valve casing, a normally closed valve controlling the flow therethrough, a bowl, a seat and its hinge-member, a cover for the seat and a hinge-member for the cover, said hinge-members having oppositely extending projections and means, comprising a lever having one arm projecting into the path of movement of each projection, for operating said valve to open the same, substantially as described.

In testimony, that I claim the foregoing, I have hereunto set my hand this twenty-sixth day of December, 1907.

GERHARD COENEN.

Witnesses:

Wm. D. BELL,
JOHN W. STEWARD.
